No. 792,891.

PATENTED JUNE 20, 1905.

W. J. FURBEE.
MINING TOOL.
APPLICATION FILED JAN. 19, 1905.

UNITED STATES PATENT OFFICE.

WILLIAM JESSE FURBEE, OF WATSON, WEST VIRGINIA.

MINING-TOOL.

SPECIFICATION forming part of Letters Patent No. 792,891, dated June 20, 1905.

Application filed January 19, 1905. Serial No. 241,762.

To all whom it may concern:

Be it known that I, WILLIAM JESSE FURBEE, a citizen of the United States, and a resident of Watson, in the county of Marion and State of 5 West Virginia, have invented a new and Improved Mining-Tool, of which the following is a full, clear, and exact description.

This invention is an improved tool for miners' use, and has for its object to provide 10 in one implement a pick, scraper, and tamping-iron, all arranged for convenient and effective use separately.

The invention consists in the novel construction, combination, and arrangement of 15 parts, as is hereinafter described, and defined in the appended claims.

Reference is to be had to the accompanying drawings, forming a part of this specification, in which similar characters of reference 20 indicate corresponding parts in all the figures.

Figure 1 is a perspective view of the improved composite tool. Fig. 2 is a longitudinal sectional view of one end portion of the 25 tool. Fig. 3 is a longitudinal sectional view of the remaining portion thereof, and Fig. 4 is an end view of the improved implement seen in direction of the arrow in Fig. 3.

Where it requires the use of explosives in 30 mining coal, a miner must use a pick to divide large lumps and dislodge such masses as are not completely loosened by a blast. He also needs a scraper for clearing out the fine chips from a drilled hole, so as to permit the 35 free insertion of a cartridge of the explosive and a tamping-bar for settling wadding upon the cartridge to render the explosive effective. Heretofore these implements have been separate and, with a cartridge-inserting stick, as 40 well as an ax and a shovel, form a miner's kit, which is a bulky assemblage of tools to be taken care of and have ready for service as needed.

The novel composite tool of my invention 45 provides a coal-pick, a scraper, and a tamping-iron in a compact and very convenient form.

The pick-head is in the form of a conical block of metal, the point 5 of which is suitably shaped for effective service and is pref-

erably formed of hardened steel. The flaring body 5^a of the pick-head is at the largest end of a diameter which will permit its free insertion into a hole that has been drilled in a coal vein, and in said end a deep cup-like 55 cavity *a* is formed, the defining circular edge thereof being sharpened to produce a scraper *b*. Centrally in the bottom of the cup *a* a tapped perforation *c* is formed longitudinally of a proper depth, and in said perforation is 60 screwed the threaded end 6^a of a shank 6, as is clearly shown in Fig. 2.

The shank 6 is made of any suitable metal, and at the opposite end is formed a threaded portion 6^b, which is screwed into the interiorly-threaded end of a cylindrical tubular handle-bar 7, as shown at *d* in Fig. 2. A sufficient length is given to the handle-bar 7 for the convenient handling and use of the composite tool, and at the opposite end thereof it 70 is interiorly threaded, as shown at *e* in Fig. 3.

A tamping-block 8 is provided, which is formed of metal cylindroconiform in contour, the smaller end of the coniform portion merging into a threaded stem 8^a, that is 75 screwed into the internal thread *e*.

A groove *g* is formed in the side of the tamping-block 8 of a sufficient depth to permit the free escape of air through it when the tamping-block is in use. 80

When the drill has been withdrawn, the fine chips or cuttings that remain in the hole may be quickly removed therefrom by the insertion of the pick-head 5^a, which may be forced down so as to cause the chips or fine dust to 85 pass upward and enter the cup *a*, whereupon a removal of the pick-head from the hole will lift a considerable quantity of the chips and discharge them.

Obviously a renewal of the operation just 90 described will clean out the drilled hole and permit the insertion of an explosive cartridge therein.

The cup *a* is also available for the removal of water that may enter a drilled hole by a 95 few insertions of the pick-head into the perforation.

When an explosive cartridge has been inserted into a hole prepared for it and suitable wadding has been placed over the cartridge 100

therein, the latter may be tamped with the block or head 8 by its reciprocation in the hole above the wadding.

The pick-head from its tapered form is well adapted to split large lumps of coal into smaller ones to enable the loading of such lumps into cars for removal from the mine, and considerable leverage is afforded by the handle-bar 7 for the moving of masses of coal that have been dislodged by an explosion.

The pick-head may also be used for removing slate from coal lumps or from the roof of a gallery in the mine, and, if desired, the head 5⁰ may be utilized as a measure of known length to space apart pillars left standing in the mine for support of the roof.

Having thus described my invention, I claim as new and desire to secure by Letters Patent—

1. A composite tool, embodying a conical

pick-head having a cup in the larger end thereof, a handle-bar projected from the bottom of the cup, and a tamping-block mounted upon the other end of the handle-bar.

2. A composite tool, embodying a conical pick-head of metal having a hardened point, a cup in the large end of the head, a shank removably secured in the bottom of the cup, a handle-bar removably mounted upon the shank, and a tamping-block mounted upon the other end of the handle-bar.

In testimony whereof I have signed my name to this specification in the presence of two subscribing witnesses.

WILLIAM JESSE FURBEE.

Witnesses:

P. M. HOGE,
M. POWELL.
